UNITED STATES PATENT OFFICE.

FREDERICK W. MÜLLER, OF HOBOKEN, NEW JERSEY.

FLUID-PRESSURE REGULATOR.

Application filed November 13, 1923. Serial No. 674,539.

To all whom it may concern:

Be it known that I, FREDERICK W. MÜLLER, a citizen of the United States of America, residing at Hoboken, county of 5 Hudson, State of New Jersey, have invented certain new and useful Improvements in Fluid-Pressure Regulators, of which the following is a specification.

My invention relates generally to apparatus for maintaining an approximately uniform fluid pressure in a receptacle to which fluid is supplied from a source of substantially constant pressure and which operates by automatically controlling the 10 flow of such fluid to such receptacle, or the exhaust of fluid therefrom, or both. While my invention may be employed to control both liquids and gases its main field of use is with gases, and it is particularly designed 15 for maintaining substantially constant counter pressures in the filling tanks of automatic bottle filling machines.

In the efficient operation of such bottle filling apparatus on carbonated liquids it is 20 essential that a counter pressure of compressed air, or carbon dioxide or other gas, be maintained in the upper portion of the filling tank to prevent as far as possible liberation of the carbon dioxide gas with 25 which the beer or mineral water in the lower zone of the tank has been charged, and to expedite the discharge of such liquid into the bottles connected to the tank for filling. This counter pressure may be unintentionally 30 increased by the liberation of gas from the charged liquid as a result of undue agitation thereof, a rise of the liquid level in the tank, or from other causes, and may be reduced by leakage of gas or fall of the liquid 35 level, etc.

Heretofore the commonly used device for controlling such counter pressure in bottle filling machines has been a safety valve on the tank set to blow off at the desired counter pressure, say 20 pounds to the square inch. Difficulties with such safety valves have arisen in practice because they are liable to stick and delay their opening or closing, are usually slow in closing so that 40 they do not stop the escape of gas until the counter pressure has fallen well below the desired figure, and sometimes get into a condition of equilibrium when partly opened so that the counter pressure gas escapes continuously, flowing through the filling tank from the source of supply. The results of

such faulty operation have been loss of gas from the source of counter pressure supply and loss of gas from the charged liquid being bottled, so that such bottled liquid became "flat" and unmarketable. 60

My invention overcomes these difficulties primarily by combining the counter pressure supply control with the blow-off device so that when either is open the other must 65 be closed, and then providing a simple, sensitive and quick acting motive apparatus for such joint control, which apparatus is automatically operated by small variations of counter pressure in the filling tank. The 70 best form of apparatus embodying my invention at present known to me is illustrated in the accompanying sheet of drawings in which:

Fig. 1 is a somewhat diagrammatic side 75 elevation and partial section of one form of apparatus, parts being broken away, and

Fig. 2 is a detail section on a plane at right angles to that of Fig. 1 showing the bleed valve, taken on line 2-2 of Fig. 1. 80

Throughout the drawings, like reference characters indicate like parts.

1 represents a receptacle capable of holding gases or liquids under pressure by reason of its connection with the filling tank of a 85 bottling machine, a portion of the cover of which tank is indicated at 2. One form of such filling tank for bottling apparatus on which my present invention may be employed is illustrated in Fig. 1 of my prior 90 Patent 1,384,538, dated July 12th, 1921. 3 represents a source of gas under pressure such as a connection to any proper storage tank, not shown, and 4 represents any standard form of pressure reducing valve which 95 will deliver the gas at a substantially uniform pressure so long as the pressure in the connection 3 is above a predetermined maximum. 5 is a section of a conduit extending from the reducing valve 4 and provided with 100 the check valve 6 opening outward from said reducing valve. The conduit section 5 connects with the vertical conduit section 7, which in turn connects through valve ports 8, 8, with the receptacle 1. 105

9 is a reciprocating valve mounted in the conduit section 7 as a valve casing and adapted to reciprocate past ports 8, so that when in the lower position shown in full lines in Fig. 1, conduit section 5 and receptacle 1 are connected, but when the valve is raised into dotted line position, communi- 110

cation between the receptacle 1 and the source of counter-pressure supply 3 is cut off. 10 is a blow-off conduit which is closed by valve 9 when the latter is in the lower position and the supply connection to receptacle 1 is open, but which is put in connection with said receptacle 1 when the valve is raised to cut off the supply of counter-pressure from 3 thereto. Valve 9 is therefore, in effect a switch valve, switching communication with receptacle 1 from the source of supply 3 to blow-off conduit 10, and vice versa.

A convenient motive apparatus for actuating switch valve 9 is represented by the closed chamber 11, having the flexible diaphragm 12 stretched across the same so as to separate the reducing valve branch connection 15 from the reducing valve 4 entering said chamber through the upper wall 24 from any communication with the receptacle 1, such as may be afforded by the pipe 16 passing through the lower chamber wall 25. This flexible diaphragm 12 is connected with valve 9 by valve rod 13, on which may be mounted another valve piston 14. In the particular construction shown, valve pistons 9 and 14 have cup packings facing one another such as are usually employed to produce a valve of the balanced type.

17 is a bleed valve for the collapsible or variable volume chamber formed by the flexible diaphragm 12 and the upper wall 24 of the rigid-walled chamber 11. This valve has a seat in the casting 18 and controls connection between the exhaust port 19 communicating with the external atmosphere and the port 23 communicating with the space between diaphragm 12 and upper wall 24. 20 is a projection from valve 17, here shown in the form of a bent strip of metal the upper end of which is adjustably secured to the spindle of valve 17 by means of the nuts 21, 21, threaded on said spindle. The lower end of projection 20 passes through an opening in the wall 24 and lies in the path of the diaphragm 12 when it rises from the lowermost position shown in full lines in Fig. 1 to any such elevated position as there indicated in broken lines.

22 is a dome fastened to the top wall 24 of chamber 11 and enclosing the bleed valve mechanism so that the same is in an airtight compartment communicating with the variable volume chamber formed above diaphragm 12. The chamber formed between diaphragm 12 and lower wall 25 of chamber 11 is connected to receptacle 1, by pipe 16.

It is evident that the upper valve piston 14 will have equal gas pressures exerted on its opposite faces when valve 9 is in its lower position, shown in full lines, as the gas passages above and below it are all connected to the receptacle 1 when the valve is in this lowermost position. The upper

valve piston 14, has a useful function when the switch valve 9 is raised into the dotted line position shown in Fig. 1, in that it will then close off the source of supply through conduit section 5 from communication with the blow-off conduit 10 through chamber 11, connection 16 and valve ports 8.

The mode of operation of the above described apparatus is as follows: Assuming that the pressure reducing valve is set at 75 20 lbs. and that there is counter-pressure of 20 lbs. in the receptacle 1 as the result of its connection with the gas zone of a filling tank, there will be an excess total pressure 80 on the upper surface of the flexible diaphragm 12, because the downward pressure on valve piston 9 counterbalances the upward pressure of the gases on a portion of the area of the undersurface of diaphragm 12 equal to the area of said valve piston 9. 85 Or, to state the matter in another form, the pressure per square inch on the two surfaces of the diaphragm 12 are equal, but there is an unbalanced downward thrust of 20 lbs. to the square inch on the valve piston 9 90 which will pull the diaphragm 12 down into its lowermost position, which is shown in full lines in Fig. 1, the pressures on the two sides of piston 14 being equal. Consequently, under the conditions assumed of the 95 existence of a constant counter-pressure of 20 pounds in receptacle 1, the parts will be and remain in the position shown in full lines in Fig. 1. If then the counter-pressure 100 in receptacle 1 falls, for any reason, the pressure reducing valve 4 will open and permit a flow of sufficient gas from the source of counter-pressures to reestablish the normal pressure of 20 lbs. in receptacle 1 and in all communicating passages, and there will be no movement of other parts of the apparatus. If, however, the pressure of gas 105 in receptacle 1 rises, as the result of the liberation of an excessive amount of the carbon dioxide with which the liquid in the filling tank has been charged, or from a considerable elevation of the liquid level in said tank, or for any other reason, the check valve 6 will close and such excess pressure 110 will be confined to the lower side of the flexible diaphragm 12. When the excessive pressure on the under side of the diaphragm, 115 above that of 20 lbs. on the upper side, becomes sufficient to overcome the downward pull of the unbalanced pressure on piston valve 9, said diaphragm and valve will begin to rise as indicated in dotted lines, and when valve 9 passes the ports 8, 8, it will 120 close off the supply of counter-pressure from conduit section 5 to receptacle 1 and simultaneously open communication between the blow-off conduit 10 and the receptacle 1.

As a result, a portion of the gases from receptacle 1 will then blow off through conduit 10, the excess pressure in receptacle 1 125 130

will be promptly relieved, the diaphragm 12, having an excess total pressure restored on its upper surface, will move back to the full line position, putting valve 9 back in 5 normal position, closing the blow-off conduit 10 and reestablishing communication between the source of counter-pressure supply and receptacle 1.

The above described rising of the diaphragm 12 and corresponding movement of valve 9 will however be slow and may be checked with the valve 9 in mid-position unless means are provided for avoiding this contingency, i. e. unless some means are provided for reducing the increased pressure which will be created in the collapsible chamber formed by the diaphragm 12 and the upper wall 24 when said diaphragm begins to rise and to reduce the volume of said 15 chamber. Evidently the gases then trapped in that upper portion of chamber 11 cannot escape unless some special means for such escape are then provided, because they cannot flow back through the reducing valve 4 and 20 they cannot return to the receptacle 1 through conduit sections 5 and 7, because there is higher gas pressure in 7 holding check valve 6 closed. To avoid this difficulty the bleed valve 17 is provided. The projection 20 25 and other movable parts of this valve are sufficiently heavy to normally hold it closed, but said projection 20 is so adjusted by means of nuts 21 that at the proper point in the upward travel of flexible diaphragm 12 it will strike the lower end of 20, lift and 30 open the bleed valve 17 and allow the gases trapped above the diaphragm to be slowly exhausted into the atmosphere and thus prevent the rise of pressure on the top of the diaphragm which would otherwise follow 35 from a reduction of volume of the collapsible chamber between 12 and 24. If desired, the bleed valve opening may be sufficient to considerably reduce such pressure so that 40 the diaphragm 12 will go up very rapidly after striking 20, and quickly shift the switch valve 9. As soon as the fall of pressure on the under side of the diaphragm 12, 45 resulting from opening blow-off conduit 10 to pipe 16, causes it to drop, the bleed valve 17 is closed, and so any constant leakage of counter-pressure through it is avoided. In short the bleed valve 17 is open only while 50 blow-off conduit 10 is open, and this is only during short periods.

The advantages of my invention comprise the prompt, positive, rapid and reciprocal action of the gas admission to, and the blow-off outlet from, the filling tank so that the 55 moment the pressure therein falls below the predetermined minimum, more gas is admitted to restore said pressure, and the moment the pressure therein rises above the predetermined maximum (which is only slightly above said minimum) the excess

pressure is blown off from the tank, and the fact that there can be no wasteful blowing through of gas from the source of counter pressure supply to the blow-off conduit. Also the use of the bleed valve 17 in preventing any stalling of the switch valve 9 in mid stroke, which might result in a leakage from the source of supply to the blow-off valve, or an undue increase of counter pressure in the filling tank, is important. 70 75

Other forms of switch valve, bleed valve and valve actuating devices might be substituted for the particular forms shown in the drawing without departing from the underlying principles of operation herein described, and some of the features of apparatus illustrated and described might be omitted without entirely departing from said principles of operation. 80

The slight spacing apart of the lower end 85 of valve projection 20 and the diaphragm 12, when the latter is in its lowermost position, by a distance less than the possible range of upward travel by the diaphragm, amounts to a "lost motion connection" between 90 said valve and diaphragm and other forms of lost motion connections might be substituted therefor.

Having described my invention, I claim:

1. In a fluid pressure regulator the combination of a fluid-tight receptacle capable of holding fluid at pressures within predetermined limits, a source of fluid supply at a substantially constant pressure slightly above the lower predetermined limit, a conduit extending from said source of supply and discharging into said receptacle, a blow-off connected to said receptacle, means controlling the flow of fluid through said conduit and said blow-off, and a device responsive to variations of pressure in said receptacle operatively connected to said controlling means, to alternately shut off the supply to said receptacle and simultaneously open the blow-off therefrom, or to close said blow-off and simultaneously open said supply connection. 95 100 105 110

2. In a fluid pressure regulator the combination of a fluid-tight receptacle capable of holding fluid at pressures within predetermined limits, a source of fluid supply at a substantially constant pressure slightly above the lower predetermined limit, a conduit extending from said source of supply and discharging into said receptacle, a blow-off connected to said receptacle, means controlling the flow of fluid through said conduit and said blow-off, and a device actuated by pressure in the receptacle approaching the upper predetermined limit operatively 115 connected to said means to open said blow-off and simultaneously close said conduit. 120 125

3. In a fluid pressure regulator the combination of a receptacle designed to hold fluids at pressures within predetermined 130

limits, a source of fluid supply at a constant pressure slightly above the lower predetermined limit, a conduit extending from said source of supply to said receptacle provided with a check-valve opening toward the receptacle, a blow-off conduit from said first mentioned conduit located between the check-valve and the receptacle, a switch valve adapted to either connect said blow-off to the receptacle while closing off the supply connection therefrom or to close said blow-off and open the supply connection to said receptacle, a closed chamber connected at one point to the receptacle and at another point to the source of supply back of the check-valve, and a movable member, operatively connected to the switch valve, located in said chamber between the above mentioned connections thereto and responsive to variations in relative pressures created therein through said connections.

4. In a fluid pressure regulator the combination of a fluid tight receptacle designed to hold the fluid at a pressure within predetermined limits, a source of fluid supply at a constant pressure slightly above the lower predetermined limit, a conduit extending from said source of supply and discharging into said fluid tight receptacle provided with a check-valve opening toward the receptacle, a blow-off conduit from said first mentioned conduit located between the check-valve and the receptacle, a switch valve adapted to either connect said blow-off to the receptacle while closing off the supply connection therefrom or to close said blow-off and open the supply connection to said receptacle, and a device responsive to variations in pressure in said receptacle operatively connected to said switch valve.

5. A combination such as set forth in claim 3 in which the movable member connected to the switch valve is a flexible diaphragm.

45 6. In a fluid pressure regulator the combination of a receptacle capable of holding fluids under pressure, a source of fluid supply at substantially constant pressure, a closed chamber with a flexible diaphragm 50 extending across the interior thereof and connected on one side of said diaphragm to the source of supply and on the other side to the receptacle, a conduit connecting the source of supply and the receptacle, which 55 conduit has a check-valve therein opening toward the receptacle, a blow-off conduit between the check-valve and the receptacle and valve means in the first mentioned conduit operatively connected to said diaphragm and controlling passage through said conduit to the receptacle and also controlling passage from the receptacle to the blow-off conduit, whereby when pressure in said receptacle exceeds that at the source of supply by a predetermined amount said dia-

phragm operates said valve means to close off the supply and connect the receptacle to the blow-off port, and when the pressure in said receptacle falls below that at the source of supply to a predetermined extent, said 70 diaphragm is moved in the opposite direction to close the blow-off and open the conduit to the receptacle.

7. The combination of a receptacle for holding fluid at pressures between predetermined limits, a source of fluid supply at a substantially constant pressure slightly above the lower predetermined limit, valve means for controlling the flow of fluid from said source of supply to said receptacle, a contracting and expanding chamber, the interior of which is connected to said source of supply, operative connections from the movable wall of said chamber to said valve means, a device for applying the pressure existing in said receptacle to exterior of said movable wall, means for preventing a flow of fluid from said chamber back to said source of supply, and a bleed-valve for said chamber and apparatus whereby said bleed valve is opened when said chamber is contracted by movement of said movable wall beyond a predetermined extent.

8. A combination such as described in claim 7 in which the last mentioned apparatus comprises a lost motion connection.

9. The combination, with an apparatus such as set forth in claim 6, of a bleed-valve for the closed chamber located on that side of the diaphragm therein to which the source of supply is connected, and means for opening said bleed-valve when the said diaphragm reaches a predetermined position in its movement toward that side of said chamber, and for closing it when said diaphragm moves toward the other side of the chamber.

10. In an apparatus for controlling the flow of fluid under pressure from a source of substantially constant pressure to a closed receptacle, which apparatus comprises a chamber with a flexible diaphragm extending across the same and connected on one side of said diaphragm to said source of supply and on the other to said receptacle, the combination, with said chamber and diaphragm, of a bleed valve in the wall of said chamber on the side connected to said source of supply and adjustable apparatus extending into the path of movement of said diaphragm, whereby said valve may be held open when the said diaphragm is within a predetermined distance from that wall of said chamber, but closes when said diaphragm is at any greater distance from said wall.

11. In an apparatus for controlling the flow of fluid from a source of supply at substantially constant pressure through a conduit receptacle in which substantially the

- same pressure is to be maintained, the combination of a closed chamber having a flexible diaphragm extending across its interior, a connection from the source of supply to 5 said chamber on one side of said diaphragm and a connection from said receptacle to said chamber on the other side of the diaphragm, a valve composed of separate pistons spaced apart and mounted on a common piston rod, which valve is connected to 10 said diaphragm and a tubular casing in which said valve reciprocates, one end of which casing is connected to said chamber on that side of the diaphragm to which said 15 receptacle is connected while the other end is open to the atmosphere, said casing having two ports, one connected to the above mentioned conduit and the other to said receptacle, said ports being spaced apart a distance less than that between the pistons of 20 said valve, and a check valve in the conduit between the source of supply and the said double ported valve casing opening away from said source of supply.
12. In an apparatus for controlling flow 25 of fluid from a source of supply at a substantially constant pressure to a closed fluid-tight receptacle and maintaining substantially the same pressure in said receptacle, the combination of a source of supply of 30 fluid at substantially constant pressure, a fluid tight receptacle containing fluid normally at approximately the same pressure, a conduit leading from said source of supply and discharging into said fluid-tight receptacle, which said conduit is provided 35 with a blow-off port and a valve adapted to close the conduit between said sources of supply and said blow-off port, or to close said port and simultaneously open the conduit, and a motor device responsive to variations of pressure in said fluid tight receptacle operatively connected to said valve.

FRED. W. MÜLLER
